ATTORNEY

UNITED STATES PATENT OFFICE.

JOHN W. SHAVER, OF BEN, ARKANSAS.

WRENCH.

1,283,332.

Specification of Letters Patent. Patented Oct. 29, 1918.

Application filed April 20, 1917. Serial No. 163,453.

To all whom it may concern:

Be it known that I, JOHN W. SHAVER, a citizen of the United States, residing at Ben, in the county of Stone and State of Arkansas, have invented certain new and useful Improvements in Wrenches, of which the following is a specification.

This invention relates to new and useful improvements in wrenches and the principal object of the invention is to provide a device of this character with means whereby the movable jaw has sliding movement on the shank toward the stationary jaw, so that the same may be adjusted to fit a nut without having to operate screw means as heretofore.

Another object of my invention is to provide means whereby the ratchet levers may readily be replaced, and the detachable pivot pins therefore eliminated.

Another object of the invention is to provide means whereby the wrench may be used in the place of several different kinds of tools.

25 A further object of the invention is to provide the jaws with engaging faces on each side of the shank so that either side of the wrench may be used.

Another object of the invention is to provide a device of this character which is simple and durable in construction, reliable and efficient in operation and one which can be manufactured and placed upon the market at a minimum cost.

35 The invention also consists in certain other features of construction and in the combination and arrangement of the several parts, to be hereinafter fully described, illustrated in the accompanying drawings and 40 specifically pointed out in the appended claim.

In describing my invention in detail, reference will be had to the accompanying drawings, wherein like characters denote 45 like or corresponding parts throughout the several views, and in which:

Figure 1 is a side view of the invention.

Fig. 2 is a rear view thereof.

Fig. 3 is a part sectional view.

Fig. 4 is a section on line 4-4 of Fig. 3.

In these figures, 1 represents the shank having the handle 2 secured thereon and also having a portion projecting beyond the handle and formed into the shape of a punch 3. At its other end said shank carries the stationary jaw 4 formed with a hammer 5

at one end and the nail pulley 6 at its other end. The shank has a circular groove 7 formed on each side thereof and teeth 8 are located in these grooves. The shank is also provided with graduations 9 representing inches and fractions thereof on one face, as shown in Fig. 3. 10 represents the sliding jaw located on the shank and provided with recesses in its four sides, the recesses on the long sides being so formed as to leave a circular, (in cross section) strip of material to span the recesses for forming journals 11 for the ratchet levers 12 and 13 which are each provided with a transverse recess in the under face thereof to be received upon said journals, and said levers located on each of the long sides of said movable jaw. These levers are held in engagement with the teeth 8 by means of the springs 14 and 15 carried by the movable jaw and engaging with the heads of the levers. The levers are provided with finger-engaging portions 16 whereby said levers may be released from the teeth so as to move the jaw. The movable jaw is provided with a double head 17 forming an engaging face on each side of the shank co-operating with like faces on the stationary jaw, so that either side of these jaws may be used to engage with the nut.

The tool may be used in the place of several different kinds of tools. For instance, the punch 3 may be used for punching holes in leather or the like, while the stationary jaw 4 may be used to drive nails or to pull 90 nails. By operating the levers 12 and 13 with the thumb and fingers of one hand, the movable jaw may be instantly placed in any desired position in relation to the other jaw and as the graduations on the shank may be seen through the opening in the movable jaw, the jaw may be set a determined distance from the stationary jaw without having to test the distance on a nut or the like.

It is thought from the foregoing that the advantages and novel features of my invention will be readily apparent.

I desire it to be understood that I may make slight changes in the construction and in the combination and arrangement of the several parts, provided that such changes fall within the scope of the appended claim.

I claim as my invention:

A wrench comprising a shank having a plurality of notches in opposite sides thereof, a stationary jaw on said shank, a movable jaw slidable on the shank and having longi-

tudinal recesses in opposite sides thereof, said recesses being formed to leave a circular, in (cross section), strip of material to span each of said recesses to form 5 journals, ratchet levers each having a transverse recess in the under face thereof to receive said journals for pivoting said levers, and flat springs having one end of each connected to said movable jaw, and the

other end adapted to engage said levers for 10 normally retaining one end of said lever in engagement with the notches in said shank.

In testimony whereof I affix my signature in presence of two witnesses.

JOHN W. SHAVER.
